UNITED STATES PATENT OFFICE.

JOHN A. HACKETT, OF PITTSBURG, PENNSYLVANIA, ASSIGNOR OF ONE-HALF TO THE L. McBRINE COMPANY, LIMITED, OF BERLIN, CANADA, FOUR-SIXTEENTHS TO ERNEST W. ORTENBERGER, THREE-SIXTEENTHS TO HENRY F. MARX, AND ONE-SIXTEENTH TO ELMER E. STOCKWELL, ALL OF PORT HURON, MICHIGAN.

TRUNK.

No. 861,173.

Specification of Letters Patent.

Patented July 23, 1907.

Application filed May 5, 1906. Serial No. 315,379.

To all whom it may concern:

Be it known that I, JOHN A. HACKETT, a citizen of the United States of America, residing at Pittsburg, in the county of Allegheny and State of Pennsylvania, have invented certain new and useful Improvements in Trunks, of which the following is a specification, reference being had therein to the accompanying drawings.

The invention relates particularly to a construction of trunk wherein a movable support is provided for the tray or trays, with mechanism for elevating the support to bring the trays upwardly into a position where they can be conveniently packed, unpacked, or removed, as desired, without the necessity of bending over the trunk, as in the ordinary construction.

The invention consists in the novel and peculiar construction of the trunk and in the arrangement and combination of the various parts as hereinafter set forth.

20 In the drawings, Figure 1 is a perspective view of my invention, with the trays detached; Fig. 2 is a sectional end view thereof; Fig. 3 is a sectional view showing the interior of the trunk; Fig. 4 is a detail sectional view of the winding drum.

25 In the drawings as thus briefly described, A represents the trunk of any ordinary construction, provided with a top B. Within the trunk is arranged a support C for one or more trays, as desired. In this instance, the support is in the form of a frame-work adapted to 30 travel in guides C' arranged in pairs upon the inner faces of the trunk ends. It consists of end sections D E, a bottom section F, and an intermediate connecting section G joining the ends. The end sections are united to the base or bottom of the support by angle 35 bars a, which form guides or ways for the trays. Between the top and bottom of the end sections are similar bars b forming ways for an intermediate tray, while similar bars c connect the upper portions of the ends with the intermediate section G to form ways or guides 40 for a third tray. The several pairs of ways described are provided at their inner ends with upturned portions d, which form stops limiting the inward movement of the trays.

The mechanism for raising and lowering the support 45 comprises a drum H, secured upon the inner face of the trunk front by means of a sleeve I, arranged within a bearing J in the trunk body, and extending through and secured to the drum by a key K. The outer end of this sleeve is flanged, as at L, bearing against an 50 annular member M on the trunk, thus holding the

parts in their proper position, and is of polygonal cross section, to receive a correspondingly-formed shank N on an operating lever O.

Secured to the drum and extending therefrom upon opposite sides of the trunk are cables P Q, running 55 over sheaves e f and g h upon the trunk bottom, upwardly over sheaves i j upon the trunk front at its upper edge, and beneath sheaves l m secured upon the under side of each end of the support and attached at their free ends to the rear wall R of the trunk at its 60 upper edge.

A locking mechanism is provided for the drum, whereby the support may be held at any point in its upward travel, consisting preferably of a ratchet o' formed upon the drum H, and a latch p secured to the 65 trunk front in operative relation to the ratchet. For the purpose of locking the latch when desired out of engagement with the ratchet, a leaf spring q is employed, which bears constantly against the latch in the manner indicated in Fig. 3.

The operating handle or lever O is detachable, so that it may be placed inside of the trunk. When it is desired to raise the trays, the lever is applied in the manner described, and upon rotation causes the cables to wind upon the drum, thus forcing the support upwardly into the position indicated in Fig. 1. By moving the latch into engagement with the ratchet, the support is held in its raised position, so that access 75 may be had to the trays, and the latter removed. Upon the replacement of the trays on the support, the 80 weight is sufficient upon releasing the lock to return the support to its initial position.

What I claim as my invention is,—

1. In a trunk, the combination with the trunk body, of a tray-supporting-frame therein arranged for vertical 85 sliding movement, a single drum, cables engaging the support and adapted to be wound upon the drum, one end of each cable being secured to the drum and the other end to the trunk body and a detachable operating member for rotating the drum.

2. In a trunk, the combination with the trunk body, of oppositely-disposed vertical guides therein, a tray-supporting-frame engaging the guides, a single drum journaled in the body, sheaves near the front corners at the top of said body cables attached to said body at the top of its back 95 and extending beneath the tray supporting frame and adapted to be wound upon the drum, and a detachable operating lever for rotating said drum.

In testimony whereof I affix my signature in presence of two witnesses.

JOHN A. HACKETT.
